J. H. DOUB

DISPATCH HOLDER

Filed Feb. 28, 1925

Inventor

J. H. Doub

SSy *Cashow & Co.* Attorneys.

UNITED STATES PATENT OFFICE.

JOHN H. DOUB, OF WALNUT, KANSAS.

DISPATCH HOLDER.

Application filed February 28, 1925. Serial No. 12,295.

To all whom it may concern:

Be it known that I, JOHN H. DOUB, a citizen of the United States, residing at Walnut, in the county of Crawford and 5 State of Kansas, have invented a new and useful Dispatch Holder, of which the following is a specification.

This invention relates to dispatch holders especially designed for transferring dispatches from station agents or the like to engineers of trains, while the trains are in operation, the primary object of the invention being to provide novel means whereby the dispatch holder may be readily detached from the handle portion thereof, thereby insuring against damage to the dispatch holder while being transferred.

Another important object of the invention is to provide means for reinforcing the dispatch holder at a point adjacent to the handle to insure against the holder splitting.

A still further object of the invention is to provide a novel form of dispatch holder wherein the same will be cheap to manufacture and at the same time be strong and durable in use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawing:

Figure 1 is an elevational view of a dispatch holder constructed in accordance with the invention.

Figure 2 is a sectional view taken on line 2-2 of Figure 1.

Figure 3 is a sectional view taken on line 45 3-3 of Figure 1.

Figure 4 is a longitudinal sectional view through one side of the handle section of the loop portion of the dispatch holder.

Referring to the drawing in detail, the 50 reference character 5 indicates the handle portion of the dispatch holder which is formed with a socket disposed at one end thereof, which socket is designed to accommodate the end portion 6 of the body portion 55 of the loop-like holder.

The body portion is formed by splitting a length of suitable wood material at a point intermediate its side edges, bending the outer portions thereof into a loop as indicated at 7, the ends of the members 60 formed by the splitting operation, being brought together in overlapped relation as shown at 8, where they are secured by means of rivets 9.

Formed in the outer surface of the loop portion or body of the dispatch holder, is a groove 10 in which the reinforcing wire 11 is positioned, portions of the wire adjacent to the end portion 6 extending transversely through the members of the body portion 65 as indicated at 11', where they pass along the inner surfaces of the loop portion to a point adjacent to the handle 5. The reinforcing wires at this point pass outwardly as at 12 where they are bent upwardly at 70 13 to lie in close engagement with the body portion.

In order to secure the ends 13 into engagement with the body portion, a securing rod 14 is provided which is wrapped around the 75 ends 13. Due to the construction of the body portion, jaws 15 are provided, between which jaws the dispatch to be delivered, is positioned. Metallic strips 16 are secured 80 to the adjacent surfaces of the jaws and are held in position by means of the rivets 17.

In the use of the device, the dispatch to be delivered is folded and positioned between strips 16 where the dispatch is gripped.

The person delivering the dispatch now holds the device by the handle 5 in such position that the engineer may pass his arm through the loop or body portion of the device, to the end that the body portion will 90 be removed from the handle 5.

From the foregoing it will be obvious that the person delivering the dispatch may tightly grip the handle 5 to prevent the body portion from twisting under wind pressure 100 in such a way that the gripping of the handle will not in any way affect the transferring of the dispatch holder from one person to another.

I claim:—

In a dispatch holder, a body portion having a groove formed exteriorly thereof and having openings communicating with the groove, a wire disposed within the groove and having portions thereof passing through 110

the openings and engaging the inner surfaces of the body portion, said wire having its ends passing laterally through the body portion and bent into close engagement with the body portion, and a securing wire wrapped around the body portion and bent ends of the wire.

In testimony that I claim the foregoing as my own, I have hereto affixed my signature in the presence of two witnesses.

JOHN H. DOUB.

Witnesses:

BEN BAILEY,
JOHN HAYDEN.
